UNITED STATES PATENT OFFICE.

EMIL D. SAINT CYR, JR., OF CHICAGO, ILLINOIS.

DESIGN FOR A SUCTION-CUP FOR SURGICAL INSTRUMENTS.

SPECIFICATION forming part of Design No. 30,951, dated June 6, 1899.

Application filed May 11, 1899. Serial No. 716,441. Term of patent 14 years.

To all whom it may concern:

Be it known that I, EMIL D. SAINT CYR, Jr., a citizen of the United States, residing at Chicago, in the county of Cook and State of Illinois, have invented and produced a new and original Design or Useful Shape for a Suction-Cup for a Surgical Instrument, of which the following, in connection with the accompanying drawings, is a full, clear, and exact specification.

In the said drawings, Figure 1 is a transverse sectional view of a suction-cup for a surgical instrument embodying my design. Fig. 2 is a plan or top view, and Fig. 3 is a perspective view.

The leading feature of my design consists of a suction-cup for a surgical instrument, having the concaved inner side A, the thin edge B, and the rib or thickened medium C.

The cup in the inner side is a true concave formed on an arc in cross-section, as shown in Fig. 1, and circular in plan view, as appears in Fig. 2, and in the center of the con-

cave is an aperture or perforation D. The thin or feather edge B of the cup is slightly beveled inwardly, so that when viewed as in Fig. 1 a flattened annular inwardly-inclined surface E is produced. The exterior of the cup, adjacent to its lower edge, rises substantially perpendicularly from the feather-edge B to the rib C, which latter is continuous throughout the circumference of the cup. From the center and exterior of the cup rises a stem F, having a cross-handle G and a knob H.

Having thus described my invention, what I claim as new therein, and desire to secure by Letters Patent, is—

The design for a suction-cup for a surgical instrument substantially as herein shown and described.

EMIL D. SAINT CYR, JR.
